UNITED STATES PATENT OFFICE.

LOUIS KREUTZKAMP, OF MASPETH, NEW YORK.

ELEVATOR.

Application filed October 26, 1928. Serial No. 315,218.

The main object of this invention is to provide an elevator which is novel in construction in so far as it uses a screw to lift or lower a freight or passenger elevator car.

5 Another object of this invention is to provide an elevator which uses a screw for lifting or lowering the car of the same, the screw being rotated by a worm drive.

Still another object of this invention is to 10 provide an elevator which uses a screw for lifting and lowering the car, said screw being so constructed as to automatically become disengaged from the car at the extreme upper and lower positions of travel.

15 A further object of this invention is to provide an elevator which uses a screw for propulsion means and is so constructed that various modified positions of the screw is possible, that is, the screw may pass through the car in 20 the center, at all the corners, at opposing positions on the car, or at diagonal corners.

The above and other objects will become apparent in the description below, in which characters of reference refer to like-named 25 parts in the drawing.

Referring briefly to the drawing, Figure 1 is a top plan view of an elevator equipped with a lifting screw which is located at and passes through the center of the car.

30 Figure 2 is a longitudinal sectional elevational view of Figure 1.

Figure 3 is a longitudinal sectional elevational view of a sidewalk elevator.

Figure 4 is a top plan view of the same.

35 Figure 5 is a top plan view of an elevator car, showing the lifting screws located at opposing positions in the well.

Figure 6 is a fragmentary sectional elevational view of a car, showing the mechanism 40 used in the construction illustrated in Figure 5.

Figure 7 is a top plan view of the lifting barrel of one of the modified forms of device, used when screws are diagonally placed in a 45 well.

Figure 8 is a sectional elevational view of the same.

Referring in detail to the drawing, the numerals 10 and 11 indicate the T-shaped guide 50 rails, common in the construction of elevators,

which are located centrally on opposing walls in an elevator well in a building or under like conditions. These T-shaped rails serve as a guide and are engaged by guide brackets 12. The guide brackets are securely mounted upon 55 the roof 13 or upon the floor, as is desired. In the type of elevator illustrated in Figures 1 and 2 a spindle 14 is provided (having electrical acme threads) and this spindle passes centrally upwardly in the well. The upper 60 and lower ends of the spindle are relieved as indicated by the numeral 15 a pre-determined distance. Near the extreme lower end a worm gear 16 is attached to the spindle and the projecting portion of the spindle, extending below the worm gear, is journaled in the aperture of a thrust bearing 17. The worm gear is adapted to be rigidly secured to the spindle and is engaged by a worm 18. The relieved portion 15 of the spindle 70 has a coil spring 19 wound about it which has sufficient tension to lift the weight of the car 13 with or without passengers or freight.

A cylinder 20, which is rigidly mounted in the car, receives the spindle therein. This 75 cylinder is relieved throughout the greater portion of its length but, at its lower end, is provided with threads which extend longitudinally in the cylinder a somewhat shorter distance than the length of the relieved portion 15. A means of control 21 may be located in the car for causing the worm to be actuated by the operator in the car or to disengage the same from the same location.

Figures 3 and 4 illustrate an elevator device in which the screw travels with the car, is stationary, but is of the same principle. These Figures 3 and 4 illustrate the common type of sidewalk lift which raises freight or passengers, at a slow speed, from a sub-cellar 90 to the sidewalk. This type of device is also provided with T-shaped rails 22 and 23 which guide a platform or carrier 24. Secured to the underside of this platform is an anchor bracket 25 which has a spindle 26 rigidly secured thereto. The spindle is located centrally of the platform and depends therefrom and is relieved at its upper end 27. A similar construction is resorted to, as previously described, that is, a coil spring 28 is 95 100

wound about the relieved portion 27 and is adapted to lift the platform and spindle when said platform and spindle are at the lower end of the well 29 and seated upon a beveled gear 30 which is actuated by a beveled pinion 31.

Figures 5 and 6 illustrate a modification of the previously described types of elevator devices. In this type, illustrated in Figures 5 and 6, the spindle 32 is also provided with 10 acme threads throughout the greater portion of its length. In this illustration, however, the spindle is supported at intermediate positions in bearing brackets 33 which are secured to the surface of the well in which the 15 elevator is located. Figure 6 illustrates the lower end of the spindle 32 and its upper end. The lower end of the spindle is relieved as indicated by the numeral 34 and has a coil spring 35 wound about the relieved portion 20 which seats upon the worm gear 36, which actuates the spindle and is rigidly secured thereto. Near the upper end of the spindle a second relieved portion 37, similar to the relieved portion 34, is provided so that when a 25 floating threaded barrel 38 arrives at the upper or lower ends of travel on the spindle, the threads will be released and will not lift or lower the car, accordingly as the case may be. In this type of device the raised relieved portion 30 at the upper end of the spindle 32 has a portion of the spindle of similar dimensions to the outside periphery of the screw continuing upwardly therefrom. This portion 39 is adapted to serve as a guide for a sleeve 40. It 35 is to be noted that both the sleeve 40 and barrel 38 are slotted longitudinally in order to pass the bearing brackets 33, as indicated in Figures 5 and 7.

Figures 7 and 8 indicate a barrel which is 40 slotted at 41 in a longitudinal direction, is threaded throughout its length, and is provided with a barrel 42, and is also provided with a mounting flange 43 which may be suitably secured to the roof or floor of the elevator 45 car. The bearing bracket and barrel illustrated in these two views are adapted to engage each other at diagonally opposite positions in a well. The split bearing bracket, consisting of elements 44 and 45, are bolted 50 to a tongue 46 which is mounted upon an L-shaped rail 47 at diagonally opposing corners in a well.

All of the types of elevators illustrated in the views operate under the same principle 55 but have slight modifications to distinguish one from the other. In the elevator illustrated in Figures 1 and 2, a single screw, centrally mounted in the well, is used, and this screw passes through a cylinder 20 located in 60 the car which is relieved throughout the greater portion of its length but is threaded at the lower end a distance less than the relieved portion 15 at the upper and lower ends of the spindle 14. As the threaded portion 65 of the cylinder is lowered beyond a po-

sition where the relieved portion 15 begins, the lifting and lowering spindle is thereafter completely disengaged from the spindle and no further rotation in the same direction in which the spindle moves will lower the car 70 any farther. Consequently, through this construction, faulty operation will not damage the parts constituting the elevator. Should the rotation of the spindle, however, be reversed, the spring 19, upon which the car seats 75 at the extreme lower level of the movement of the car, will lift said car and cylinder 20 so that the threads in said cylinder will again engage the threads of the spindle and cause the car to be raised to its upper level. 80

The device illustrated in Figures 3 and 4 operates in the same manner as that previously described, but in this case the spindle 26 is not rotatable, but is rigidly mounted with the platform or carrier 24 and passes 85 through a rotatable beveled gear 30 having a threaded aperture therein.

In the device illustrated in Figures 5 and 6 the elevator construction dispenses with the use of the T-shaped rails which are required 90 in an elevator where a single worm is used. In Figure 6 the threaded barrel 38 engages on the screw and becomes disengaged at the upper and lower limits of its travel by riding upon the relieved portions 34 and 37. Mounted 95 on the car and also rigid with the same are sleeves 40 which are slidably mounted on the spindle and do not engage the same. The barrel 38 has an ear 49 which is mounted on studs 50, and on opposite surfaces of this ear 100 springs 48 are seated which tend to give a cushion effect to the travel of the car as it comes to an abrupt stop, either in raising or lowering.

It is to be noted that certain changes in 105 form and construction may be made without departing from the spirit and scope of the invention.

I claim:

1. In an elevator, a car, a threaded spindle 110 engaging said car, a cylinder mounted on said car having said spindle passing therethrough, threads in said cylinder, said spindle having a reduced diameter at the upper and lower ends thereof, the length of said reduced diameter being greater than the length of threads in said cylinder, and means for urging the threads in said cylinder into engagement with the threads of said spindle when said car is at the lower limits of its travel. 115

2. In an elevator, a car, a threaded spindle engaging said car, a cylinder mounted on said car having said spindle passing therethrough, threads in said cylinder, said spindle having a reduced diameter at the upper and lower ends thereof, the length of said reduced diameter being greater than the length of threads in said cylinder, and yieldable means adapted to lift said car into en- 120 125 130

gagement with the threads of said spindle when said car is at the lower limits of its travel.

3. In an elevator, a car, a threaded spindle engaging said car, a cylinder mounted on said car having said spindle passing therethrough, threads in said cylinder, said spindle having a reduced diameter at the upper and lower ends thereof, the length of said reduced diameter being greater than the length of threads in said cylinder, a coil spring mounted at the lower end of said spindle, said coil spring being adapted to have said cylinder in said car seated thereon and urge said cylinder and car upwardly into position where the threads in said cylinder engage the threads of said spindle.

4. In an elevator, a car, a threaded spindle engaging said car, a cylinder mounted on said car having said spindle passing therethrough, threads in said cylinder, said spindle having a reduced diameter at the upper and lower ends thereof, the length of said reduced diameter being greater than the length of threads in said cylinder, a coil spring mounted at the lower end of said spindle, said coil spring being adapted to have said cylinder in said car seated thereon and urge said cylinder and car upwardly into position where the threads in said cylinder engage the threads of said spindle, and a split sleeve mounted on said car adapted to serve as a guide for said car.

In testimony whereof I affix my signature.
35 LOUIS KREUTZKAMP.
